(57) **CLAIM**

The ornamental design for a surgical knife safety handle, as shown and described.

DESCRIPTION

FIG. 1 is a perspective view of an embodiment of a surgical knife safety handle showing our new design;

FIG. 2 is a top view of the surgical knife safety handle shown in FIG. 1;

FIG. 3 is a left side elevational view of the surgical knife safety handle shown in FIG. 1, the right side elevational view (not shown) being a mirror image of the left side elevational view of FIG. 3;

FIG. 4 is a front elevational view of the surgical knife safety handle shown in FIG. 1; and,

FIG. 5 is a rear elevational view of the surgical knife safety handle shown in FIG. 1.

The broken line showing of the surgical knife safety handle, blade and blade support is for illustrative purposes only, and forms no part of the claimed design. Broken lines are also used to show surface circular features on the grip portion of the surgical knife safety handle, such surface circular features also forming no part of the claimed design.
